UNITED STATES PATENT OFFICE

167,009

PLANT ROOT RECEPTACLE

Angelo Tersini, San Jose, Calif.

Application January 17, 1950, Serial No. 7,301

Term of patent 14 years

(Cl. D35—3)

To all whom it may concern:

Be it known that I, Angelo Tersini, a citizen of the United States, residing at San Jose, in the county of Santa Clara and State of California, have invented a new, original, and ornamental Design for Plant Root Receptacle, of which the following is a specification, reference being had to the accompanying drawing, forming a part thereof.

In the drawing:

Figure 1 is a top plan view of a plant root receptacle showing my new design.

Fig. 2 is a side elevational view of the receptacle.

Fig. 3 is a horizontal sectional view in the plane of line 3—3 on Fig. 2, on a reduced scale.

Fig. 4 is a bottom plan view on the scale of Fig. 3.

I claim:

The ornamental design for a plant root receptacle, as shown.

ANGELO TERSINI.
